UNITED STATES PATENT OFFICE.

ROBERT PHILLIPS, OF NEW ALBANY, INDIANA.

DESIGN FOR A SLEEVE-BLANK.

SPECIFICATION forming part of Design No. 31,055, dated June 20, 1899.

Application filed April 18, 1899. Serial No. 713,516. Term of patent 7 years.

To all whom it may concern:

Be it known that I, ROBERT PHILLIPS, a citizen of the United States, residing at New Albany, in the county of Floyd and State of Indiana, have invented and produced a new and original Design for a Blank for Garment-Sleeves, of which the following is a specification, reference being had to the accompanying drawing, forming part thereof, in which 10 the figure is a face view of the sleeve-blank.

The leading or material feature of my design consists in the blank for the sleeve forming the subject-matter of the accompanying illustration.

This design is best shown in the drawing, 15 in which the blank is represented with the opposite sloped edges A A, the point B, and the notch C.

Having described my invention, what I claim as new, and desire to secure by Letters 20 Patent, is—

The design for a sleeve-blank, as herein shown and described.

ROBERT PHILLIPS.
